UNITED STATES PATENT OFFICE

1,997,396

CRANKLESS MECHANISM

Thomas L. Sherman, Buffalo, N. Y., assignor to
Michell-Crankless Engines Corporation, New
York, N. Y., a corporation of New York

Application April 18, 1934, Serial No. 721,074

10 Claims. (Cl. 123—58)

This invention relates to crankless mechanisms and particularly to crankless engines of the type shown in Michell Patent No. 1,613,116.

In the patent mentioned there is shown an engine having a power shaft and a cylinder parallel to the shaft, a pair of slants or slant plates mounted on the shaft and a piston coating with each slant and disposed in the cylinder, the pistons acting in opposed relation to transmit the power to the shaft through the slants.

It has also been proposed to obtain more impulses per revolution of the shaft by using two aligned cylinders in each unit, a pair of pistons in each cylinder and three slants on the shaft to receive and transmit the power from the pistons to the shaft. Such a construction is shown in Patent No. 1,781,008 to Greening et al.

The construction illustrated diagrammatically in the last patent referred to is not satisfactory or practical, particularly for an engine having an even number of cylinders equally spaced around the shaft, as shown in said patent. Such an arrangement permits cylinders in each unit to fire simultaneously and so causes a doubling up of the forces arising from combustion, thus giving rise to severe torque and bending stresses and to unnecessarily heavy loadings on the shaft.

This invention has for its salient object to overcome the conditions and to solve the problems above set forth and to provide a crankless mechanism of the opposed piston type having two aligned cylinders in each unit with slants so arranged as to lessen maximum stresses on the central portion of the shaft and on the bearings, to lessen maximum shear stresses from the power torque and to provide a greater number of torque impulses per revolution of the shaft.

Another object of the invention is to provide an engine of the type specified so constructed and arranged as to permit the use of cylinder units of identical design in the same engine, i. e., having the same relation of scavenge and exhaust porting.

Further objects of the invention will appear from the following specification taken in connection with the drawing which forms a part of this application, and in which

Fig. 1 is a longitudinal sectional elevation of an engine constructed in accordance with the invention; and

Fig. 2 is a transverse sectional elevation of the engine shown in Fig. 1.

In the embodiment of the invention illustrated in the drawing, the engine which is of the barrel type is provided with a casing 10, a shaft 11 and a

plurality of cylinder units A, B, C and D arranged around the shaft in parallel relation thereto and equally spaced therefrom.

Each of the cylinder units comprises a pair of cylinders E and F which are disposed in alignment with each other. Each cylinder has mounted therein a pair of oppositely acting pistons, the pistons being indicated as 15, 16, 17 and 18.

The shaft 11 is mounted in bearings 20, 21, 22 and 23 and has secured thereto three slants or slant plates X, Y and Z. The piston 15 has secured thereto a yoke 25 provided with pivoted bearing members such as slipper pads 26 and 27 which engage and coat with the slant plate X to transmit the motion of the piston to the shaft 15. A rod 28 is secured to one end of the yoke 25 and is mounted in guide bearings 29. In the form of the invention shown, a piston 30 is connected to the end of the rod 28 and is disposed in an air compression cylinder 31 from which air 20 can be forced through suitable conduits to the scavenge ports of the engine.

The piston 18 has secured thereto a yoke 31 similar to the yoke 25 and having pivoted bearing members or slipper pads 32 and 33 which 25 engage and coat with the slant Z to transmit the motion of the piston to the shaft 11. A rod 34 is connected to the yoke 31 and is mounted in bearings 35.

The pistons 16 and 17 are connected by a yoke 30 having bearing members or slipper pads 41 and 42 which engage and coat with the central slant Y and transmit the movement of the pistons to the shaft 11.

The cylinders E and F are each provided with intake ports for the scavenging air and with exhaust ports. The intake and exhaust ports in cylinder E are indicated at 45 and 46 and the intake and exhaust ports for cylinder F are indicated at 47 and 48.

The slants X, Y and Z are angularly disposed relative to each other and are so mounted on the shaft that the piston 18 will lead the piston 17 in cylinder F and will therefore open the exhaust port 48 earlier than the opening of the scavenging port 47. Also the piston 16 in the cylinder E will open the exhaust port 46 earlier than the opening of the scavenging port 45 by the piston 15.

The angle of advance of the slant Z over the slant Y is shown in Fig. 2 at Z, O, Y and the angle of advance of the slant Y over the slant X is shown in Fig. 2 at Y, O, X. By this arrangement the cylinder F will fire ahead of the cylinder E by the angle between any two of the slants. If the engine as illustrated comprises four cylin-

der units there will be eight impulses given to the shaft 11 per revolution.

It will be evident from the foregoing description that the engine constructed and arranged as set forth will lessen the maximum loadings on the shaft bearings and the maximum stresses in the central portion of the shaft arising from forces tending to produce bending movements and torque therein. Furthermore, a greater number of torque impulses per revolution will result in a smoother operation of the engine.

Although one specific embodiment of the invention has been particularly shown and described it will be understood that the invention is capable of modification and that changes in the construction and in the arrangement of the various cooperating parts may be made without departing from the spirit or scope of the invention, as expressed in the following claims.

20 What I claim is:

1. Crankless mechanism comprising a shaft, a plurality of cylinder units arranged around and parallel to said shaft, each unit comprising a pair of aligned cylinders, three slant plates mounted on said shaft and arranged in angular relation to each other, a pair of oppositely acting pistons in each cylinder, driving connections between the outer pistons and the end slant plates, and driving connections between the inner pistons in said cylinders and the other slant plate.

25 2. Crankless mechanism comprising a shaft, a plurality of cylinder units arranged around and parallel to said shaft, each unit comprising a pair of aligned cylinders, three slant plates mounted on said shaft and arranged in angular relation to each other, an air inlet port and an exhaust port in each cylinder, a pair of oppositely acting pistons in each cylinder, said ports being controlled by said pistons, driving connections between the outer pistons and the end slant plates, and driving connections between the inner pistons in said cylinders and the other slant plate.

30 3. Crankless mechanism comprising a shaft, a plurality of cylinder units arranged around and parallel to said shaft, each unit comprising a pair of aligned cylinders, three slant plates mounted on said shaft and arranged in angular relation to each other, an air inlet port and an exhaust port in each cylinder, a pair of oppositely acting pistons in each cylinder, said ports being controlled by said pistons, driving connections between the outer pistons and the end slant plates, and driving connections between the inner pistons in said cylinders and the other slant plate, the slant plates being so angularly disposed relative to each other that the exhaust ports in the cylinders will be opened prior to the opening of the inlet ports for the scavenging air.

35 4. Crankless mechanism comprising a shaft, a plurality of cylinder units arranged around and parallel to said shaft, each unit comprising a pair of aligned cylinders, three slant plates mounted on said shaft and arranged in angular relation to each other, a pair of oppositely acting pistons in each cylinder, driving connections between the outer pistons and the end slant plates, and driving connections between the inner pistons in said cylinders and the other slant plate, the slant plates being so angularly arranged relative to each other that the piston connected to one end slant will lead the oppositely acting piston in the same cylinder which is connected to the intermediate slant and the other piston connected to said intermediate slant will lead the piston connected to the other slant.

5 5. Crankless mechanism comprising a shaft, a plurality of cylinder units arranged around and parallel to said shaft, each unit comprising a pair of aligned cylinders, three slant plates mounted on said shaft and arranged in angular relation to each other, an air inlet port and an exhaust port in each cylinder, a pair of oppositely acting pistons in each cylinder, the inlet port in one cylinder and the exhaust port in the other cylinder being controlled by the pistons operatively connected to the central slant and the other ports in said cylinders being controlled by the pistons operatively connected to the outer or end slants, driving connections between the outer pistons and the end slant plates, and driving connections between the inner pistons in said cylinders and the other slant plate.

10 6. Crankless mechanism comprising a shaft, a plurality of cylinder units arranged around and parallel to said shaft, each unit comprising a pair of aligned cylinders, three slant plates mounted on said shaft and arranged in angular relation to each other, an air inlet port and an exhaust port in each cylinder, a pair of oppositely acting pistons in each cylinder, the inlet port in one cylinder and the exhaust port in the other cylinder being controlled by the pistons operatively connected to the central slant and the other ports in said cylinders being controlled by the pistons operatively connected to the outer or end slants, driving connections between the outer pistons and the end slant plates, and driving connections between the inner pistons in said cylinders and the other slant plate, the slant plates being so angularly disposed relative to each other that the exhaust ports in the cylinders will be opened prior to the opening of the inlet ports for the scavenging air.

15 7. Crankless mechanism comprising a shaft, a plurality of cylinder units arranged around and parallel to said shaft, each unit comprising a pair of aligned cylinders, three slant plates mounted on said shaft and arranged in angular relation to each other, an air inlet port and an exhaust port in each cylinder, a pair of oppositely acting pistons in each cylinder, the inlet port in one cylinder and the exhaust port in the other cylinder being controlled by the pistons operatively connected to the central slant and the other ports in said cylinders being controlled by the pistons operatively connected to the outer or end slants, driving connections between the outer pistons and the end slant plates, and driving connections between the inner pistons in said cylinders and the other slant plate, the slant plates being so angularly arranged relative to each other that the piston connected to one end slant will lead the oppositely acting piston in the same cylinder which is connected to the intermediate slant and the other piston connected to said intermediate slant will lead the piston connected to the other end slant.

20 8. Crankless mechanism comprising a shaft, a plurality of cylinder units arranged around and parallel to said shaft, each unit comprising a pair of aligned cylinders, three slant plates mounted on said shaft and arranged in angular relation to each other, a pair of oppositely acting pistons in each cylinder, driving connections between the outer pistons and the end slant plates, and driving connections between the inner pistons in said cylinders and the other slant plate, the slant plates being so angularly arranged relative to each other that one end slant will operate in advance of the central slant and said

central slant will operate in advance of the other end slant.

9. Crankless mechanism comprising a shaft, an even number of cylinder units arranged around and parallel to said shaft, each unit comprising a pair of aligned cylinders, three slant plates mounted on said shaft and arranged in angular relation to each other, a pair of oppositely acting pistons in each cylinder, said ports being controlled by said pistons, driving connections between the outer pistons and the end slant plates, and driving connections between the inner pistons in said cylinders and the other slant plate, the slant plates being so angularly arranged relative to each other that one end slant will operate in advance of the central slant and said central slant will operate in advance of the other end slant.

10. Crankless mechanism comprising a shaft, a plurality of cylinder units arranged around and parallel to said shaft, each unit comprising

a pair of aligned cylinders, three slant plates mounted on said shaft and arranged in angular relation to each other, an air inlet port and an exhaust port in each cylinder, a pair of oppositely acting pistons in each cylinder, said ports being controlled by said pistons, driving connections between the outer pistons and the end slant plates, and driving connections between the inner pistons in said cylinders and the other slant plate, the slant plates being so angularly arranged relative to each other that one end slant will operate in advance of the central slant and said central slant will operate in advance of the other end slant.
